UNITED STATES PATENT OFFICE.

JOSEPH M. COALE, OF BALTIMORE, MARYLAND.

OIL-CUP.

SPECIFICATION forming part of Letters Patent No. 479,246, dated July 19, 1892.

Application filed February 24, 1892. Serial No. 422,621. (No model.)

To all whom it may concern:

Be it known that I, JOSEPH M. COALE, a citizen of the United States, residing at Baltimore, in the State of Maryland, have invented 5 certain new and useful Improvements in Oil-Cups; and I do declare the following to be a full, clear, and exact description of the invention, such as will enable others skilled in the art to which it appertains to make and 10 use the same, reference being had to the accompanying drawings, and to the letters of reference marked thereon, which form a part of this specification.

My invention relates to oil-cups, especially 15 those used in locomotives. It is found that the constant jarring of the engine loosens the caps of the oil-cups, so that they are frequently lost. This induces the machinist to use extra force in screwing on the caps, so 20 that when it is attempted to remove one of them for the purpose of filling the cup the entire cup is liable to be unscrewed from the rod or guide to which it is attached by its threaded stem; but if the cups are set up too 25 hard when screwed into place the brass stems are in danger of being twisted off. Moreover, in guide-cups which have a conical or needle valve to regulate the feed the sediment tends to follow down the valve and clog the 30 feed-duct.

My invention overcomes all these difficulties; and it consists in an oil-cup which can be filled without unscrewing the cap, which has a wrought-iron stem strong enough to be 35 firmly screwed into the rod or guide, and which has a conical feed-valve that cannot become clogged.

In the accompanying drawings, Figure 1 is a vertical section of an oil-cup for a connecting-rod or side rod. Fig. 2 is a vertical section of an oil-cup for a guide-bar or cross-head. Fig. 3 is a top plan view of Fig. 1; and Fig. 4 is a top plan view of Fig. 2, showing the cover for the filling and ventorifices open. 40

The body A of my oil-cup is externally screw-threaded at its upper end to receive the internal thread on the cylindrical flange b of the cap B. Two holes b' b² are drilled through the cap to serve as filling and vent orifices. 45 They are slightly countersunk to facilitate the insertion of the spout of the oil-can. Since 50

the holes are of equal size, the spout can be applied to either of them, the other serving as a vent. To protect these holes from dirt, a cover is provided. It may be attached to 55 the cap in various ways; but I prefer the construction shown, in which a plate C, of suitable size to cover the holes, is provided with a spindle c, passing vertically through a central hole in the cap B, midway between the 60 holes b' b². The plate is of such a width that when turned transversely to a line joining the holes it will expose them, as shown in Fig. 4.

Different modes of locking the plate when 65 covering the holes will suggest themselves; but I prefer that shown in the drawings. A shallow groove or recess b³ is formed in the cap B, adapted to receive the plate C. The groove and plate are preferably provided with 70 beveled edges to insure a tight fit. A convenient mode of forming the groove is to cut it across an elevated portion b⁴ of the cap. The holes b' b² lie in the bottom of the groove on either side of the spindle c. An annular 75 flange b⁵, surrounding the spindle, sustains and guides it in a vertical position. A collar c' is fastened to the lower end of the spindle and forms a seat for a helical spring D, which encircles the spindle and abuts against the 80 under side of the cap around the flange b'. The spring holds the cover C tightly to its seat, but permits it to be lifted by means of the knob C' and turned to a position transverse of the groove b⁴ when the cup is to be 85 filled, as shown in Fig. 4 and by dotted lines in Fig. 2. With this construction it is unnecessary to remove the cap B except for cleaning or repairs, and said cap may therefore be screwed so tightly upon the cup that 90 it will not become loosened by the jar of the engine. The location of the screw-threads on the outside of the cup, where the oil cannot get at them, assists in maintaining a tight joint. As an additional safeguard, however, 95 I may provide the collar c with two radial arms c², which, when the cover C is lowered into its seat, drop in behind the lugs a on the inside of the body A, and thus afford an absolute lock for the cap B. The screw-threaded 100 stem by which the cup is attached to the rod or guide is usually made integral with the

body A, as shown in Fig. 2. My improved stem A' is made of wrought-iron and is screwed into a tapped opening in the bottom of the cup with a collar a' to abut against the under side of the bottom. Its upper end projects into the cup, where it receives a lock-nut. I prefer to utilize the yoke E for this purpose, making it separate instead of integral with the cup. Its use as a lock-nut does not interfere with its primary function, that of supporting the screw F for adjusting the feed of the plunger-valve G, commonly used in rod-cups. Guide-cups usually have a conical valve to adjust the feed. When located at the bottom of the cup, the apex of this cone being downward, the sediment in the oil follows down the valve and clogs the feed-duct. I obviate this by the arrangement shown in Fig. 2. The duct H commences at the apex of a conical seat a². The valve I is a screw working in a tapped hole in the yoke E, and having in its lower end a conical recess i, which coacts with the seat a². By this construction the sediment tends to fall away from the duct H and to collect in the annular well a³ around the yoke.

Having thus described my invention, what I claim, and desire to secure by Letters Patent, is—

30 1. An oil-cup having filling and vent holes in its cap, a cover adapted to open and close said holes by a partial rotation, and a spring holding said cover upon the cap, substantially as described.

35 2. An oil-cup having filling and vent holes in its cap, a cover for said holes, consisting of a plate mounted upon a stem, on which it has both a rotatory and an axial sliding movement, and a spring holding said plate against the cap, substantially as described.

3. An oil-cup having filling and vent holes and an oblong groove in its cap, a cover for said holes, consisting of a plate adapted to be received in said recess, and means for holding said plate yieldingly in the recess, substantially as described.

4. An oil-cup having filling and vent holes and a transverse groove in its cap, a cover for said holes, consisting of a plate adapted to be received in said groove, said plate being rotatable and also axially movable, and having a spring holding it in said groove, substantially as described.

5. The combination, with the oil-cup A, of the cap B, provided with a transverse groove 55 and having the holes b' b² opening into said groove, the plate C, having a spindle c midway between said holes, the collar c' on said spindle, and the spring B, compressed between said collar and the cap B, substantially as described.

6. The combination, with the oil-cup A, having the lugs a, and the cap B, having the filling and vent holes and the groove, of a plate C, having a spindle c, provided with the 65 collar c' and arms c², and the spring D, substantially as described.

7. The combination, with an oil-cup A, of a tubular wrought-iron stem screwed into the bottom of said cup, a yoke E, screwed upon the inner end of the stem, and a screw working in the yoke above and in line with the bore of the stem to regulate the feed, substantially as described.

In testimony whereof I affix my signature in presence of two witnesses.

JOSEPH M. COALE.
